(No Model.)

D. N. OSYOR.
SEPARABLE TERMINAL FOR CONDUCTORS.

No. 538,083.

Patented Apr. 23, 1895.

UNITED STATES PATENT OFFICE.

DAVID N. OSYOR, OF COLUMBUS, OHIO, ASSIGNOR TO JOSEPH A. JEFFREY
OF SAME PLACE.

SEPARABLE TERMINAL FOR CONDUCTORS.

SPECIFICATION forming part of Letters Patent No. 538,083, dated April 23, 1895.

Application filed November 28, 1893. Serial No. 492,268. (No model.)

To all whom it may concern:

Be it known that I, DAVID N. OSYOR, a citizen of the United States, residing at Columbus, in the county of Franklin and State of Ohio, have invented certain new and useful Improvements in Separable Terminals for Conductors, of which the following is a specification, reference being had therein to the accompanying drawings.

10 This invention relates to an improved detachable terminal or contact device for connecting electric conductors which are more or less portable or movable with other conductors, particularly for connecting portable conductors with such as are stationarily secured upon wall-supports or similar places.

Figure 1 is a face view of a device embodying my improvements. Fig. 2 is a side view. Fig. 3 is a side view showing the parts in the 20 positions occupied at the time of coupling or uncoupling. Fig. 4 is a cross-section on the line $x-x$ of Fig. 1. Fig. 5 shows the terminals of the detachable parts after uncoupling them from the stationary parts. Fig. 6 is a 25 longitudinal section of one of the detachable terminals. Fig. 7 is a perspective of a terminal or contact piece to which one like that in Fig. 6 can be detachably coupled and locked.

In the drawings, A indicates the part of 30 the device which I shall term the stationary contacts or terminals, although I wish it to be understood that many of the features of the present invention can be employed where it is desired to connect the ends of two portable or removable conductor sections.

The part A comprises two insulated sections a, a' . These are preferably castings with base pieces a^2 , plates a^3 , binding-screws at a^4 and grooves or throats a^5 . The peripheries or external surfaces of the plates are substantially concentric with the inner ends of the grooves or throats a^5 .

The portable terminals comprise two metallic parts indicated by B, B', which are 45 preferably castings with sockets at b for the reception and the fastening of the ends of conductor wires. They are separated from each other by means of insulating material C. Each is formed with the shank b' , a short 50 tubular pinto b^2 and a locking lug b^3 . The tubular pintles b^2 are in line with each other

transversely and the two parts are fastened together sufficiently firmly by means of a pin D of insulating material which passes through the pintles. Preferably the shank parts b' are 55 shaped so as to be as nearly as possible semi-circular in cross-section as such shape I have found to be convenient, but in that respect there can be more or less variation. The pintles are adapted to enter and be seated in 60 the aforesaid throats or passages a^5 in the stationary contact A. By examining the drawings, it will be seen that they can be so introduced when the terminals B, B' are in their relative positions shown in Fig. 4. The 65 distance between the pintles b^2 and the lugs b^3 is such that when the parts are in the said positions in Fig. 4, the terminals B, B' are 70 permitted to move inward between the parts a, a' until the pintles come to the bottom of the throats or passages a^5 . Then, if the terminals B, B' be rocked or turned down in the 75 position shown in Fig. 2, it will be impossible to separate them from the terminals a, a' , the lugs b^3 acting to stop any outward movement of the pintles.

In order to bind the opposing surfaces of the metal firmly together, the peripheries of the parts a, a' are preferably shaped so that they have a cam-like action upon the lugs b^3 , 80 so that the latter and the pintles are drawn tightly against the metal on the parts a, a' , and consequently a superior electric contact is provided.

I am aware of the fact that detachable terminals and contacts of numerous sorts have 85 been devised for various purposes, many of the earlier ones employing springs or elastic bars or sheets of metal; but I believe myself to be the first to have devised detachable or 90 terminal contacts possessing the features of construction which have been hereinbefore described.

One of the present character is particularly well adapted for use in connection with mining 95 apparatus, where the devices which are used are liable to be subjected to severe usage. In such cases the contacts a, a' are secured to an insulating base A adapted to be fastened to a wall or other support; or they may be secured directly or indirectly to the resistance box or rheostat of the mining machine. In 100

either case, it is necessary to attach and detach to such contacts portable conductor sections at frequent intervals. I have had experience with a number of sorts of such detachable contacts or terminals in connection with the use of mining and similar machinery, and find the one herein to be superior to any with which I have become acquainted.

I have shown one of the several ways of embodying my invention, but do not limit myself to precisely the features shown and described, as modified devices will suggest themselves to those skilled in such matters without departing from the essential feature 15 of the invention which relates to having a conductor coupling formed in two members, a male and a female part which can have a rocking or axial motion as to each other as well as a movement bodily one toward the 20 other, together with means substantially such as described which will act to force together the contact surfaces and also act when in certain positions to prevent the terminals from moving bodily away from each other.

25 What I claim is—

1. The herein-described detachable terminals for a portable conductor section having the insulated bars B, B', provided with pintles or projections and locking lugs, in combination with the opposing insulated contacts a, a', having grooves or throats for the said pintles and locking surfaces for engaging the said lugs, substantially as set forth.

2. The detachable terminals or contacts B, 35 B' formed as counterparts of each other with a sheet of insulating material between them, and having the herein-described pintles and locking lug in combination with opposing contact pieces having throats or passages for 40 said lugs and arranged substantially as set forth, whereby the detachable parts cannot be removed until they are thrown into an unusual angular position, substantially as described.

3. A portable conductor section having flexible conductors, enlarged metal terminals secured together with insulating material be-

tween them, each terminal being provided with a contact part, and a wedge like or cam like pressure device, said terminals being adapted to be simultaneously and detachably connected to opposing terminals formed with sockets or cavities and with cam like or wedge like means for coacting with those on the aforesaid terminals, substantially as set forth. 50

4. The combination with the stationary terminals a, a', insulated from each other and having sockets or recesses, of the portable conductor section having insulated terminals B, B', with contacts in opposition to contacts on the parts a, a', one of said pairs of terminals being detachably fitted to the other, and having devices rigid therewith adapted to bear or press against the other during the rocking movement, substantially as set forth. 55

5. The combination with the stationary insulated terminals having electric contact surfaces and the sockets or seats a⁵ opposite to each other, of the opposing detachable terminals secured together but insulated from each other and having the projections b² adapted to be moved bodily in the aforesaid sockets or recesses a⁵ when the terminals B, B' are in one axial position, and means for locking the said projections b² against such bodily movement when the terminals are in another radial position, substantially as set forth. 70

6. The combination with the terminal a' having the socket a⁵ and a cam like edge a³, of the detachable terminal B having the pintle b², adapted to move into and out from the 80 socket a⁵ and also to rock therein, and the projection b³ adapted to engage with the aforesaid edge a³ on the stationary terminal, and means for insulating the said terminals B and a', substantially as set forth. 85

In testimony whereof I affix my signature in presence of two witnesses.

DAVID N. OSYOR.
